UNITED STATES PATENT OFFICE.

CHARLES E. CAIN, OF WAUPACA, WISCONSIN, ASSIGNOR OF ONE-HALF TO
IRA C. EDWARDS, OF MINNEAPOLIS, MINNESOTA.

THILL OR POLE COUPLING.

SPECIFICATION forming part of Letters Patent No. 695,030, dated March 11, 1902.

Application filed December 12, 1901. Serial No. 85,562. (No model.)

To all whom it may concern:

Be it known that I, CHARLES E. CAIN, a citizen of the United States, and a resident of Waupaca, in the county of Waupaca and 5 State of Wisconsin, have invented certain new and useful Improvements in Thill and Pole Couplings; and I do hereby declare that the following is a full, clear, and exact description thereof.

10 My invention has for its object to provide simple, economical, antirattler, and dust-proof thill and pole couplings, the same consisting in certain peculiarities of construction and combination of parts hereinafter particularly set forth with reference to the accompanying drawings and subsequently claimed.

Figure 1 of the drawings represents a side elevation of a thill or pole coupling in accordance with my invention and illustrates a portion of same in connection with an axle, the latter being in transverse section; Fig. 2, a sectional view indicated by line 2 2 in the first figure; Fig. 3, a similar view indicated by line 3 3 in the second figure; Fig. 4, a like view indicated by line 4 4 in the third figure, and 25 Fig. 5 an end view of a slotted and recessed cylindrical block constituting a movable part of the coupling.

Referring by letter to the drawings, A indicates a circular holder having an upper radial slot *b* and a horizontal rear shank *c*, the shank being shown made fast to an axle B, against the under side of same, by means of an ordinary clip C and nuts *d* run on the clip 30 ends extended through apertures provided in said shank. Fitting the holder A is a radially-slotted cylindrical block D, having a circular central recess *e* therein deeper than its slot *f*, said recess and slot being intercepting. 35 Recess *e* in block D is circular, and a spiral spring E therein is under sufficient normal compression against the inside of the holder A to prevent accidental displacement of said block. Holder A, block D, and spring E, con-

40 structed and arranged as above specified, constitute the axle-section of my improved coupling, the thill or pole section being a suitably-bent iron F, that is preferably widest and necessarily flat at the rear end. Coupling- 45 section F is shown recessed at the rear to provide side projections *g*, it being also provided

with a rear central longitudinal recess *h* and a transverse angular slot *i* forward of the latter recess, separated therefrom by a web *j* of the metal. The thickness of the rear portion 55 of coupling-section F is such that it can be readily engaged with slot *b* of holder A and slot *f* of block D aforesaid when these two slots are in register, as is normally the case. To facilitate the engagement, one side of the 60 recessed and slotted portion of coupling-section F has a flaring indenture *k*, the narrowest portion of which is immediately adjacent to slot *i* and as wide as the length of same.

To join the coupling-sections, the thill or 65 pole section F is held in position to have its recessed and slotted end enter the registering slots *b f* of holder A and block D of the axle-section, pressure being exerted against spring E by the recessed portion *h* of said thill or 70 pole section. The spring having been sufficiently compressed slot *i* in the thill or pole section of the coupling is engaged by holder A of the axle-section of said coupling, said thill or pole section being then movable with 75 the block D in said holder.

The ends of block D are shown provided with semicircular continuations *f'* of the recess *f* therein, the diameter of these continuations being such that shoulders *f''* are left in 80 said recess to abut the rear edge portions of the thill or pole section of the coupling flanking the recess *h* therein, and the projections *g* of said coupling-section serve to exclude dust from said continuations of the block-recess when the union of both coupling-sections is effected. However, it is practical to omit the recess continuations of the block D and projections *g* of the thill or pole section 85 F of the coupling. A cap G is shown in rigid 90 connection with the thill or pole section of the coupling, arranged to exclude dust from slot *b* of the axle-section of said coupling when said thill or pole section is swung past said slot.

95 Expansive force of spring E serves to press thill or pole section F of the coupling and the block D snug against the block-holder A of the axle-section of said coupling with which they are engaged. Hence compensation is had 100 for wear and loose play to prevent rattling in the aforesaid coupling.

Having thus described my invention, what I claim as new, and desire to secure by Letters Patent, is—

1. A thill or pole coupling comprising a radially-slotted circular holder having a shank attachable to an axle, a holder-fitting cylindrical block having a radial slot and a circular recess intercepting each other therein, a spiral spring in the block-recess normally under compression against the inside of said holder, a longitudinally-recessed and transversely-slotted thill or pole iron engageable with the aforesaid holder against resistance of the spring, and a holder-slot dust-cap in connection with the thill or pole iron.
2. A thill or pole coupling comprising a radially-slotted circular holder having a shank attachable to an axle, a holder-fitting cylindrical block having a radial slot and a circular recess intercepting each other therein, a spiral spring in the block-recess normally under compression against the inside of said holder, and a longitudinally-recessed and transversely-slotted thill or pole iron engageable with the aforesaid holder and block against resistance of the spring.
3. A thill or pole coupling comprising a radially-slotted circular holder having a shank attachable to an axle, a holder-fitting cylindrical block having a radial slot and a circu-

lar recess intercepting each other therein, a spiral spring in the block-recess normally under compression against the inside of said holder, a longitudinally-recessed and transversely-slotted thill or pole iron engageable with the aforesaid holder against resistance of the spring, and a holder-slot dust-cap in connection with the thill or pole iron.

4. A thill or pole coupling comprising a radially-slotted circular holder having a shank attachable to an axle, a holder-fitting cylindrical block having a radial slot and a circular recess intercepting each other therein, a spiral spring in the block-recess normally under compression against the inside of said holder and a longitudinally-recessed and transversely-slotted thill or pole iron having rear side projections constituting dust-guards for continuations of the block-slot inward from shoulders in the same abutting the rear edge portion of said iron when the latter is engaged with the aforesaid holder and block against resistance of the spring.

In testimony that I claim the foregoing I have hereunto set my hand, at Waupaca, in the county of Waupaca and State of Wisconsin, in the presence of two witnesses.

CHARLES E. CAIN.
